FISHING REEL

Joseph C. Clark, Orlando, Fla.

Application May 13, 1958, Serial No. 50,863

Term of patent 14 years

(Cl. D31—4)

FIG. 1

FIG. 2

Fig. 1 is a right side elevation of a fishing reel showing my new design.

Fig. 2 is a left side elevation thereof.

Fig. 3 is a front end elevation thereof.

The dominant features of the design are shown in full lines.

I claim:

The ornamental design for a fishing reel, as shown and described.
